Inventor,
T. H. Willson

UNITED STATES PATENT OFFICE.

T. H. WILLSON, OF HARRISBURG, PENNSYLVANIA.

BLOWER.

Specification of Letters Patent No. 31,844, dated March 26, 1861.

To all whom it may concern:

Be it known that I, T. H. WILLSON, of Harrisburg, in the county of Dauphin and State of Pennsylvania, have invented certain new and useful Improvements in Blowers; and I do hereby declare that the following is a full, clear, and exact description of the same, reference being had to the accompanying drawings and to the letters of reference 10 marked thereon.

The nature of my invention consists in constructing and arranging the several parts of this blower in the manner herein after described.

15 In the annexed drawings Figure 1 represents a side view with one side of the case removed. Fig. 2 is a top view of the blower wheel. Fig. 3, is a view of a portion of the blower case. Fig. 4, is a perspective 20 view of one of the wings or arms of the blower wheel.

In the figures A, represents the blower case which is cast in two parts and in the form represented in the drawing said case 25 being very similar in shape to the snail shell. Each portion of the case is cast with an opening Z, near its center and with a flange around its periphery by or through which the two portions are secured together. 30 Packing may be inserted between the two sections of the case, by means of which the capacity of the case may be increased or diminished to some degree.

D, D, represent a series of arms or wings 35 which when placed and secured together in proper manner around the shaft B, constitute the blower wheel. The wings or arms D, D, are cast in the peculiar shape represented in the Figs. 1, 2, 4, Fig. 4, representing more fully and clearly the shape of the 40 said wings. The wings are cast with heels, as shown in Fig. 4, which form a hub, when several of said wings are fitted together—and this hub is held together by means of

two metallic bands which are shrunk upon 45 or over the projecting sides of the heels. c, represents a comb or flange cast upon one side (the back) of the wing which serves to give strength to said wing, and which fitting against the wing next to it in the 50 wheel, goes to form with the heels of the wings as constructed a wheel with a self supporting center. The front portion of the wing is cast in a curved form and hollowing, having sides a, a, which converge from near 55 the heel where they begin, to the point of the wing. These wings receive the air from the openings Z, and force it in the direction of the arrow around the grooves in the case seen from x, to x'. When air is forced 60 it escapes through the most accessible channel, and being prevented from escaping from the wings by the sides a, a, it passes out freely through the grooves to the mouth of the case.

65 The shaft B, has its bearings in journal boxes formed in supports cast upon each side of the case.

d, d, represent the bands which are shrunk around the heels of the wings, or the hub 70 formed by said heels.

Having thus fully described my invention what I claim as new and desire to secure by Letters Patent is—

1. The employment of the blower wheel 75 as constructed, composed of a series of wings or arms (D) cast in the form represented and being secured together by means of the devices before described, all as and for the purpose set forth.

2. In combination with the subject of the first claim I claim the fan case constructed in the shape and manner herein represented.

THOS. H. WILLSON.
